INVENTOR

John W. Cosgrove
By his Attorney
William W. Howard

UNITED STATES PATENT OFFICE.

JOHN W. COSGROVE, OF MEDFORD, MASSACHUSETTS, ASSIGNOR TO UNITED SHOE MACHINERY COMPANY, OF PATERSON, NEW JERSEY, A CORPORATION OF NEW JERSEY.

MACHINE FOR INSERTING FASTENINGS.

1,250,285.

Specification of Letters Patent. Patented Dec. 18, 1917.

Application filed April 5, 1915. Serial No. 19,225.

To all whom it may concern:

Be it known that I, JOHN W. COSGROVE, a citizen of the United States, residing at Medford, in the county of Middlesex and State 5 of Massachusetts, have invented certain Improvements in Machines for Inserting Fastenings, of which the following description, in connection with the accompanying drawings, is a specification, like reference characters 10 on the drawings indicating like parts in the several figures.

This invention relates to machines for inserting fastenings and more particularly to fastening inserting machines for use in the 15 manufacture of boots and shoes.

The invention is herein illustrated as embodied in a machine especially designed to insert staples of fine wire through the upper and channel lip or rib of a sole and to 20 clench the staples upon the lip or rib to constitute permanent shoe fastenings.

An essential element of a machine for inserting such staples is the means for clenching the projecting ends of the staples since 25 the precision and certainty with which the clenching is effected depends to a large extent upon the holding power and efficiency of the staples. In the use of machines of this type upon shoes in which the staples are 30 clenched in a channel provided in the sole, considerable difficulty is experienced both in positioning the clenching anvil in the channel to effect a proper clenching of the staples and also in feeding the shoe along in progressive stages to locate successive fastenings.

One of the objects of the present invention, therefore, is to provide improved clenching means which will be especially 40 adapted to operate in a channel in the sole.

To this end the invention aims to provide a clenching anvil comprising means for clenching the projecting ends of the staple and means adapted to enter the channel and 45 open it up in advance of the clenching means, thereby facilitating the accurate clenching of the staples in the channel and at the same time facilitating the feeding of the shoe into the different staple receiving positions.

50 Other objects and features of the invention will appear from the following description when considered in connection with the

accompanying drawings and will then be pointed out in the claims.

In the drawings:—

Figure 1 is a perspective view of a clenching anvil embodying the present invention;

Fig. 2 is a perspective sectional detail illustrating the operation of the clenching anvil in the channel of a shoe sole;

Fig. 3 is a cross section of a portion of a shoe showing the clenching anvil in operative position thereon.

The staple forming and inserting machine in which the present invention is especially 65 designed to be embodied is of the type shown in the United States Letters Patent to W. J. Drey, No. 1,011,592, granted Dec. 12, 1911 to which reference may be had for a full description of its construction and operation. 70 It will be understood however, that the invention is not restricted to use in machines of the type shown in said Letters Patent.

The machine of said Letters Patent comprises, briefly, a staple forming mechanism, 75 a staple driving mechanism arranged to insert a staple through the upper and channel lip or rib of the insole and a clenching anvil which co-operates with a throat to press together the parts through which the staples 80

are inserted and to clench the projecting ends of the staples which, in a shoe of the type having a channel in the sole for the reception of the inseam stitches, are located in the channel. In accordance with the 85 present invention, the clenching anvil 2, the general construction of which is the same as that shown in the above mentioned patent,

has a relatively thick channel entering nose comprising a substantially vertical channel 90 lip engaging face 3 having a staple clenching cavity 5 formed therein near one side of the nose in the line of staple drive, the leading part 6 of the nose 3 being laterally extended from the clenching cavity 5 and 95 tapering gradually from said clenching cavity to its leading edge to open the channel and turn up the channel lip against the cavity in the nose upon shoe feeding movement relatively to the anvil 2. It will be 100

observed that the anvil nose has its upper face 8 inclined upwardly and backwardly over the clenching cavity 5, the construction being such that the plow-shaped part 6 and

the surface 8 progressively turn up the channel lip and open the channel in advance of the clenching cavity 5 upon shoe feeding movement relatively to the anvil. The vertical face 3 of the anvil preferably intersects the bottom face 9 of the anvil throughout its length so that it forms a comparatively long sharp edge whereby the anvil may be forced down into the bottom of the channel 10 as shown in Fig. 3 and also offers a substantial bearing against which the shoe may be held during the fastening inserting operation.

In presenting a shoe to the machine to receive a fastening the plow-shaped portion 6 of the anvil readily enters the channel in the sole and opens it up sufficiently to enable the anvil to be positioned in the channel so that it may coöperate with the throat 12, 20 Fig. 3, in pressing together the parts of the upper through which a staple is to be inserted and to insure the position of the clenching cavity in line with the plane in which the staple is driven. As the shoe is moved relatively to the anvil into position to receive other fastenings the plow-shaped nose of the anvil readily forces its way along the channel and the inclined face 8 engages the channel lip 13 and turns it up, as shown in 30 Fig. 2, out of the way of the staple clenching cavity so that there is no danger of its becoming caught between the clenching cavity and a staple as often happens with the clenching anvil now in use. It will be noted 35 that a particular advantage obtained by the use of the clenching anvil above described is that the shoe may be moved along in progressive stages with the anvil always in position in the channel and the channel opened up to 40 receive the clenching cavity while with the anvils heretofore used, the channel had to be opened up and the anvil positioned for each staple inserting operation.

Having described my invention, I claim as

new and desire to secure by Letters Patent 45 of the United States:—

1. In a machine for inserting fastenings, an anvil for clenching staples inserted through the upper and channel lip of a shoe, comprising a relatively thick channel entering nose having a staple clenching cavity formed therein in the line of staple drive, the leading part of said nose being laterally extended from the clenching cavity and tapering gradually from said clenching cavity 55 to its leading edge to open the channel and turn up the channel lip against the clenching cavity in the nose upon shoe feeding movement relatively to the anvil.

2. In a machine for inserting fastenings, an anvil for clenching fastenings inserted through the upper and channel lip of a shoe, comprising a relatively thick nose formed to present a channel lip engaging face having a clenching cavity formed therein in the line of fastening drive, and a channel opening plow offset laterally from said nose in position to turn up successive portions of the channel lip to open the channel in advance of the nose.

3. In a machine for inserting fastenings, an anvil for clenching staples inserted through the upper and channel lip of a shoe, comprising a relatively long nose shaped and arranged to enter the channel and to present a substantially vertical channel lip engaging face 3 having a staple clenching cavity 5 formed therein near one side of said nose, and at the other side of said nose having its upper face 8 inclined upwardly and backwardly over the clenching cavity to form a plow 6, 8 for progressively turning up the channel lip and opening the channel in advance of the clenching cavity upon shoe feeding movement relatively to the anvil.

In testimony whereof I have signed my name to this specification.

JOHN W. COSGROVE.
